UNITED STATES PATENT OFFICE.

FRANCIS G. BOSWELL, OF WASHINGTON, DISTRICT OF COLUMBIA.

ELECTRO POSTMARKING-MACHINE.

1,024,552.

Specification of Letters Patent.

Patented Apr. 30, 1912.

Application filed February 13, 1909. Serial No. 477,522.

To all whom it may concern:

Be it known that I, FRANCIS G. BOSWELL, a citizen of the United States of America, residing at Washington city, District of Columbia, have invented a new and useful

Electro Postmarking-Machine.

This invention pertains to that class of printing machinery, popularly known, as post-marking or stamp canceling machines. Broadly speaking, such machinery may be divided into two classes; the one, in which the canceling cylinder or hub, revolves continually, and the other, in which the die hub or cylinder is held normally stationary, being rotated only at the moment of canceling the stamp, and imprinting the postmark. To this latter class, belongs the following described invention, which seeks to provide new and novel means, for liberating the die hub, and for putting the same into motion, at the moment of liberation.

It also contemplates other novel means, which causes quick and efficient separation of mail matter, and the subsequent stacking of the same after cancellation.

An electric register for counting each piece of mail canceled, and an automatic inking device, for keeping the ink roll supplied with ink, constitute with the features mentioned above, the salient parts of the machine, on which it is desired to obtain Letters Patent.

The invention further provides for an increased efficiency, and speed in machines of this class, and also for the concentration of all moving parts within the smallest practicable area. To this end, a column *a* is designed to support the lower bed plate *b*, with the aid of the cap screws *c*. Standards *d* integral with the bed plate *b* sustain the upper bed plate *e* (flat head screws *f* penetrating the standards through this bed plate) and the space contained between the two bed plates, provides room for those parts of the machine, vital to its operation, but not of necessity exposed. The column *a* being hollow forms a suitable compartment, for the driving motor, the machine being belt driven, is adapted for use in connection with either alternating or direct current motors, irrespective of their speed or shape.

The conspicuously new features, are electrically operated, and are thus assured of quick and positive action, while provision is made, for insuring all contacting surfaces

against the oxidation, ordinarily attending the making and breaking of a circuit.

A stacker back entirely automatic in its action, and a stacker extension arm easily and quickly operated, conclude the objects for which the apparatus is designed.

In the exposition of this specification, a particular form of machine is adhered to, but the invention is not confined to this especial form. Its application in practical fields may necessitate certain changes and alterations, which the right is claimed to make, provided such changes and alterations are comprehended by the appended claims.

Referring to the drawings which accompany this specification and form a part thereof: Figure 1 is a top plan view of the machine showing the upper bed plate and parts of the machine mounted thereon. Fig. 2 is a sectional plan view taken slightly below the upper bed plate, and showing the vital parts of the machine, which are carried between the two bed plates, and showing in dotted lines the auxiliary feed belt. Fig. 3 is a front elevation of the machine, parts being broken away so as to display the driving mechanism for the machine. Fig. 4 is a detail elevation of the driver mechanism, the die hub or cylinder and the impression roller, showing its sectional shaft, the parts of which are connected by universal joints. Fig. 5 is an end elevation of the two bed plates, showing the automatic stacker back and its guiding frame in side view, and also illustrating the star wheel; in this figure the remaining parts of the machine, other than those above mentioned, are omitted. Fig. 6 is a detail view showing the upper and lower bed plates in section, clearly illustrating the auxiliary feed belt, and the tightening means therefor. Fig. 7 is a view showing the method for taking up the slack in the idler drive belt. Fig. 8 is a detail fragmentary sectional view of the automatic stacker back, clearly illustrating the manner in which it is guided upon the rods of the stacker tray. Fig. 9 is a sectional view through the electric register, clearly illustrating the essential features in the edge view. Fig. 10 is a sectional view on line 10-10 of Fig. 9, showing the parts of the register in side elevation. Fig. 11 is a detail perspective view showing the feed roll 33, and the manner in which the same is movably mounted in the bed plate, and the

means for adjusting said feed roll. Fig. 12 is an enlarged sectional view of a portion of the structure shown in Fig. 4, showing in detail the cushioning means carried by the 5 detent, whereby the detent plate is cushioned; in this figure it is to be understood that the detent plate has been retarded, and the cushioning means under tension; the detent plate is cushioned for the 10 distance indicated by the line $x-x$. Fig. 13 is a detail perspective view of the detent, showing the cushioning means in its normal condition. Fig. 14 is a sectional view on line 14—14 of Fig. 49, showing the particular construction of the driver, which construction is vital to the operation thereof. Fig. 15 is a sectional view on line 15—15 of Fig. 14. Fig. 16 is a view showing the driver, that is shown in Figs. 12, 14 and 15, 15 disassembled, showing the leader member and the follower member. Fig. 17 is a detail view of the holder and its stud, in which holder the brush for contacting with the driver is mounted. Fig. 18 is a sectional 20 view on line 18—18 of Fig. 17. Fig. 19 is a top plan fragmentary view, showing the ink pump, the means or magnet for operating the plunger or piston of the pump, and the means for closing and opening the circuit 25 for the said magnet. Fig. 20 is a detail sectional view of a portion of the pump, through which the ink is forced upon the inker idler roll. Fig. 21 is a detail perspective view of the means for closing and opening the circuit of the magnet, that is shown 30 in Fig. 19. Fig. 22 is a sectional view on line 22—22 of Fig. 19. Fig. 23 is a sectional view vertically through the automatic stacker back and its frame, showing opposite positions of the moving parts. Fig. 24 35 is an enlarged detail, sectional view through one side of the stacker back and its frame. Fig. 25 is a sectional view transversely through Fig. 24 upon line 25—25, so as to 40 show clearly the construction of the stacker back. Fig. 26 is a detail plan view of the upper bed plate, showing one of the switch idler rolls and showing the slot which allows 45 for movement thereof. Fig. 27 is a sectional view on line 27—27 of Fig. 26, clearly 50 illustrating the L-shaped bracket member for supporting the switch idler roll. Fig. 28 is a detail sectional view through the inker idler roll, the ink pad roll, and the 55 bracket or mounting for such rolls, showing clearly the manner in which the bracket or mounting is secured to the upper bed plate. Fig. 29 is a detail sectional view of a portion 60 of the upper bed plate, showing the carrier belt and the rolls therefor. Fig. 30 is a sectional view on line 30—30 of Fig. 29. Fig. 31 is a top plan view of a portion of the upper bed plate, showing the switch, the switch 65 idler roll and the contact block and blow-out magnet. Fig. 32 is a sectional view on

line 32—32 of Fig. 31. Fig. 33 is a detail view of a portion of the upper bed plate, showing a modification of the auxiliary feed belt, in other words, a flat feed belt, which may be used in lieu of the belt shown in 70 Figs. 1, 3 and 6, and also illustrating the manner in which motion is transmitted to said belt. Fig. 34 is a fragmentary detail view showing a modification of the separating means that is shown in Fig. 1; in this 75 figure the separating means proper is adjustable by means of the thumb nut. Fig. 35 is a sectional view on line 35—35 of Fig. 34, showing the parts upon an enlarged scale, and illustrating the manner in which 80 the thumb nut is held from rotating when once adjusted. Fig. 36 shows a further modification of the separating means, showing modified means for holding the separating means or cone in adjusted positions. 85 Fig. 37 is a detail view of a portion of the structure that is shown in Fig. 36. Fig. 38 is a view showing a modification of separating means, which comprise fingers. Fig. 39 is a fragmentary view, showing in side 90 elevation the structure that is shown in Fig. 38. Fig. 40 is a detail view of the meshing gears for operating the stacker extension arm. Fig. 41 is a detail sectional view, showing clearly the manner in which the 95 stacker extension arm is guided. Fig. 42 is a sectional view on line 42—42 of Fig. 9, showing clearly the detail structure of the register mechanism. Fig. 43 is a detail perspective view of one form of switch which 100 is contacted with by an advancing letter for closing the circuit upon the detent magnet and the magnet 91. Fig. 44 is a detail plan view of the construction shown in Fig. 43, showing in dotted lines the reverse position 105 of the pawl 75. Fig. 45 is a detail perspective view of a portion of the frame of the stacker tray shown in Fig. 5. Fig. 46 is a sectional view through one of the members or slides of the stacker back shown in 110 Fig. 1, clearly illustrating the ball bearing feature, so as to allow the stacker back to move easily by the weight of the mail. Fig. 47 is a sectional view vertically through the structure shown in Figs. 43 and 44, showing 115 clearly the manner of securing the tongue 73 and pawl 75 upon the stud 74. Fig. 48 is a sectional view showing the detail structure of the mounting of the roller 28 to the bed plate e , clearly illustrating the adjustable feature thereof. Fig. 49 is an enlarged sectional view of the structure shown in Fig. 4, showing in detail the particular features of the driver, the drive hub or cylinder and the impression roller which is 120 driven from motion of one section of the sectional shaft of the driver, through the medium of the gear 51 and the co-operating gear of the said section of the sectional shaft; the impression roller's shaft com- 125 130

prises flexible connected sections, so as to allow movement of the said roller; in this figure, the detent is rather too small to show its detail construction. Fig. 50 is a detail 5 sectional view showing the die cylinder and its detent plate, the detent and its detent magnet, showing the cushioning means as being dispensed with. Fig. 51 is a detail view of the sheaves 142 and their supports. Fig. 52 is a detail cross sectional view of 10 the die cylinder. Fig. 53 is a sectional view upon line 53—53 of Fig. 32. Fig. 54 is a detail sectional view transversely through the lower portion of the stacker back 360, 15 showing more clearly the wedge or bevel shape of the back and how the three pieces forming the back merge together, and in order to form the compartments 369 and 370.

20 Reverting to Fig. 1 and designating the parts by numerals, so that a clearer understanding may be had: Number 1 is the auxiliary feed belt fence, secured to the bed plate *e*, by cap screws 2, which pass through the projections 2^a. Numbers 3, 4, 5 and 6 are the carrier belt fences, also fastened to bed plate *e* in the same manner as fence 1, projections 3^a, 4^a, 5^a and 6^a being clamped down by the cap screws 3^b, 4^b, 5^b and 6^b. 25 Number 7 is the assisting arm mounted loosely on the stud 8, and thrown normally backward, by the spring 9, the length of throw being limited by the lug 10 on the arm, coming in contact with the projection 35 11 on the stud. The assisting arm moves over the auxiliary feeding belt 12, and in rear of the mail (which is placed upon the feed belt) in order to assist in feeding the mail to the separating mechanism. The 30 mail when placed upon the belt is positioned in front of the arm 7. The auxiliary feed belt 12 runs over loose sheaves 13, carried by the rods 14, set in boxed bearings 15, in the bed plate. This feed belt is endless in 35 form, and the upper portions of the belt, as seen clearly in Fig. 1, pass from each loose sheave 13, at one end of the auxiliary feed belt, to each sheave directly opposite. The 40 portions of the feed belt which are disposed beneath the bed plate *e* pass from each sheave at one end to each sheave diagonally opposite thereto, as shown clearly in dotted lines in Fig. 2. The portions of the feed belt 12 which pass from the corner loose 45 sheaves 12^a are disposed downwardly and toward one another, in order to form the looped portion 12^b of the belt, which travel about the sheaves 16, 16^a and the pulley 18, as clearly disclosed in Fig. 6 of the illustrations. 50 This belt also runs over a belt tightener, composed of sheaves 16 and 16^a, mounted on frame 17, which also carries the boxed pulley 18. This whole frame swivels on the lower bed plate, being connected 55 thereto by the screw stud 19. A wing screw 60

20 serves to hold the frame 17 stationary, when it has been moved to tighten the belt 12. This belt is driven from one of the tightener pulleys, by the bevel gear 21, meshing with a bevel gear 22 on the face of 70 the pulley 16^a, the bevel gear 21 receiving motion from the shaft 23, on which it is fastened. The shaft 23 has a thrust bearing in the top of the box 24, and a steady bearing 25 set in bracket 26, which straddles the 75 auxiliary belt and is secured to the bottom of the upper bed plate by suitable cap screws. The sheave 27, is also fastened to the shaft 23, and is the medium through which the shaft receives motion. 80

In Fig. 33, an auxiliary flat feed belt is shown, which may be employed in lieu of the auxiliary feed belt shown in Figs. 1, 3 and 6, and is designated by the numeral 500, and is operated by an endless belt 501, similar to that shown in Fig. 2, and which travels about the sheave or pulley 502, the shaft 503 of which is journaled in suitable bearings of the upper and lower bed plates. The shaft 503 has movable therewith a bevel 90 gear 504, which meshes with a bevel gear 505 carried upon the shaft 506, on which and movable therewith is a roll 507, about which the auxiliary flat feed belt travels. This auxiliary flat feed belt 500 also travels about a roll 508 carried by and movable with the shaft 509, which is mounted in suitable bearings of the upper bed plate. The bearings for the shafts 506 and 509 are similar to the box bearings 15 shown in Fig. 6, and 95 for that reason it is not necessary to illustrate the same in Fig. 33. 100

Numeral 28 is the feed belt tightener pulley secured to the shaft 29, which is carried by the bracket bearing 30 designed to slide in a recessed portion of the upper bed plate, being capable of enough longitudinal adjustment to take up all slack in the feed belts 31; this adjustment being maintained by the cap screw 30^a which, passing through the slotted portion 30^b of the bracket, holds it to the bed plate. The shaft 29 carries at its lower end a sheave 32 from which the feed belts 31 are driven. These feed belts in turn drive the feed roller 33 which carries on its periphery, midway between the two belts, the feed rubber 34. The feed roller is loosely mounted on the stud 35 set in and projecting through a slide (composed of the parts 35^a and 35^b united by the screws 110 35^c) which moves in a slotted portion of the bed plate, this slot being cut on the arc of a circle, the center of which is the shaft 29. This method gives flexibility to the feed roller without affecting the tension of the 115 feed belts. The flat spring 36 holds the stud 35 normally against the front of the slot, but this stud is adjustable backward by means of the hand wheel 37 and rod 37^a which connects with the rod 38 through the 120 125 130

bevel gears 39. This rod 38 passes through bracketed bearings 40, and threads into the box nut 41 which slides in a recessed portion of the crank 42 and at the same time is capable of a swiveling motion on the pins 43. On the fence 4 brackets 390 and 391 are mounted, being made integral with the fence. The brackets 390 and 391 carry bearings in which the separator cone shaft 392 is journaled, while the bracket 391^a acts as a steady bearing for the separator gear shaft 52. On the shaft 392 the separator cone is mounted, its surface being provided with the spirally formed steps 393, while that portion of the frustum near the base carries the separator rubber 394. A bevel gear 395 is fastened on the shaft 392 at the end remote from the cone and meshes with the bevel gear 396 carried by the shaft 52. The cone is then driven in a clockwise direction, (when viewed from the apex) by the gear 50 which, meshing with the drive gear 51, receives motion and transmits it by the shaft 52 to the bevel gear 396. A modified form of separator may be used, as shown in Figs. 34, 35, 36 and 37, in which case a swinging fence 397 is used in place of the fence 4, while the steady bearing of shaft 52 is transferred to the bed plate *e*. A hinge 398, integral with the fence 397, sets over the shaft 52 on that portion which extends through the bed plate on which it has a thrust, and the hinge is so formed as to straddle the feed gear 396. With the separator on this swinging fence, it is unnecessary to have the feed roll 33 adjustable, for the swinging property of the fence makes possible the adjustment of the separator cone. This adjustment is accomplished by the adjustment screw 399, the head of which rests behind the bifurcated extension 400 of the projection 401, this projection being a part of the fence 397. The other end of the screw passes through the lug 402 (stationary on the bed plate) and enters the knurled nut 403, while the spiral spring 404, which is under compression between the lug 402 and the bifurcated part 400, tends to force the fence 397, together with the separator cone, toward the feed roller. By turning the nut 403, the position of the cone with respect to the feed roller can be varied.

Another form of adjustment screw is shown in Figs. 34 and 35, in which form, the screw is hinged to the separator fence at the point 405, where it is capable of a swiveling movement. Passing through the lug 406, to the top of which the flat spring 407 is secured, it threads into the nut 408, provided on its periphery with grooves for the reception of the spring. With this form of adjustment screw, any movement of the separator fence must necessarily cause a movement of the screw, but the spring 407

being long enough to remain in contact with the nut 408 for the extreme movement of the screw, any predetermined adjustment of the nut 408 is not upset.

Still another form of separator is shown in Figs. 38 and 39 which comprises fingers. The finger 44 is mounted on the solid spindle 45, which drops through the hollow spindle 46. This spindle 46 carries at its upper end and directly below the finger 44, the finger 47. These two spindles connect, below the upper bed plate, with the reciprocating arms 48 and 49. The hollow shaft 46 is provided with suitable bearing features in the upper bed plate. The gear 50 serves to drive the separating fingers, by meshing with the drive gear 51. The gear 50 is mounted on the shaft 52, which carries the eccentrics 53. Suitable eccentric straps 54 and connecting rods 55 unite the eccentrics with the reciprocating arms.

The carrier belt 56, running over the pulleys 57 and 58 and rolls 57^a and 57^b, is driven by pulley 57, which in turn is driven by the sheave 59, through the shaft 60. Brackets 61, dropped from the upper bed plate, form suitable bearings for the shaft 60, while roll 57^a is set in bearings (formed on the top of the upper bed plate) in which it is retained by the plates 57^c and screws 57^d. The roll 58 is held in a manner similar to roll 57^a, but on the under side of the upper bed plate by thrust plates 57^e and 57^f. The carrier belt tightener pulley 57^b is carried by a bracket 62 which slides in a track formed in the upper bed plate in which it is held by the cap screw 63.

Numerals 65 and 66 are the switch idler rollers. Grooves 65^a are cut in their circumferences to provide clearance for the switch tongue 73, there being only one of said grooves shown, as shown in Figs. 3 and 27. Each of these rollers is carried on its shaft (which is integral with the roller) in suitable L-shaped bearings 67, swiveling from the upper bed plate on screw studs 67^a, with the legs of the L-shaped bearings movable through slots cut in the bed plate. The rollers are further provided with sheaves 68 from which each receives motion.

The stacker idler rollers 69 and 70 are substantially the same as the switch idler rollers having bearings 71 and sheaves 72, identical respectively with 67 and 68, and mounted in the same way on screw studs 71^a.

The switch is composed of the tongue 73 swiveled on the stud 74 directly above the pawl 75. A shoulder on the stud keeps the tongue and pawl from dropping to the bottom of the stud and a suitable washer 76 and screw 77 prevent them from rising off the top. The pawl is capable of movement between the studs 78 and 79, while the tongue is normally held back against the pillar 80 by the spring 81, the tension of

which spring is governed by the screw 82 and the knurled nut 83 set in the box 84. The spring 81 is of greater strength than the spiral spring 85, which is connected between 5 the pin 86 on the pawl and pin 87 on the tongue and serves to hold the pawl against the stud 78, when the tongue is against the pillar 80; the spring 85 then contracting on that side of the stud 74 nearest the stud 10 78. When the tongue 73 is away from the pillar 80 whither it is thrown by the approaching letter, the spring 85 contracts on the opposite side of the stud 74 and draws the pawl 75 over against the stud 79, during 15 which operation the pawl 75 passes and makes contact with the contact block 88, thus closing the circuit on the detent magnet 95. The exact way in which this is accomplished will be brought out in a description 20 of the generator circuits to be described later.

The contact block is made up of the block 88 set on pivotal bearings 89 and 90, the pivot 89 being stationary in the lower leg 25 of the contact blow-out magnet 91, and the pivot 90 adjustable through the upper leg, by means of a threaded portion and the jam nut 92. A spring 93 holds the block 88 in line with the magnet legs, and at the same time allows it a pivotal movement which is imparted to it by the pawl 75, when it makes contact with the block. The face of the block, normally remote from the pawl, is provided with an insulated section, so that 30 the pawl having closed the circuit of the detent magnet on its forward movement, will not do so in returning. The function of the blow-out magnet is to provide a magnetic field where the circuit is made and broken, so 35 that the arc resulting from opening the circuit will be blown out and the oxidation of the contact surfaces thereby prevented. The blow-out magnet 91 is mounted on an insulating base 94 and secured to the upper 40 bed plate in any suitable manner.

The detent magnet 95 is set in the frame 45 96 bolted to the upper bed plate, which frame is provided with the arm 97. A knurled screw 98 and lock nut 99 constitute 50 means for adjusting the plunger core 100 vertically through the center of the magnet. This plunger is designed to disengage the 55 detent 101 from the detent plate 104, by hitting the tail of the detent, thus drawing the nose down. The detent is set in a slotted out portion of the upper bed plate and rides on a pin 102, which pin is set up in the bottom of the upper bed plate *e*, where it is held by thrust plates 102^a, secured by screws 60 102^b. A spring 103 serves to hold the tail of the detent down.

The detent 101 comprises two parts, the part 101^a, which oscillates upon the pin 102, and the part 101^b. The part 101^a is provided with a V-shaped tongue 101^c, which is

received by the V-shaped groove 101^d of the part 101^b; in this way the two parts of the detent have a sliding connection. In the end 101^e, a screw pin 101^f is threaded, which extends into a supplemental rectangular 70 groove 101^g of the part 101^b, and is designed to be contacted with by the shoulder 101^h, that is to say, when the part 101^b is extended its full limit, as shown in Fig. 12. The contacting of the shoulder and the pin is gradually reached as the spring 101^k is distended by the engagement of the nose of the detent with the notch 105 of the detent plate, which causes the part 101^b to have a sliding action or movement upon the part 101^a, that is to say, at the time the die cylinder and detent plate are rotating as one body and the circuit of the detent magnet and the magnet 91 is broken. The spring 101^k has one of its ends secured to a projection 101^m, while its 80 other end is secured to the rear portion 101ⁿ of the part 101^b, as shown clearly in Figs. 12 and 13. The spring 103 is interposed between the top of the recess 101° of the bed plate *e* and the projection 101^m, one end of 90 the spring 103 being secured to the bed plate in the said recess, while the other end surrounds an extension 101^s of the said projection, as shown clearly in Fig. 12.

The structure of detent, as above described, is provided for the purpose of cushioning the die cylinder, when the same is retarded, that is, when the detent magnet circuit is broken, so as to prevent wear upon the said detent plate and the detent, which 100 would otherwise be if there were no cushioning means provided.

The detent plate 104 is of the shape shown in Figs. 12 and 13; the notch 105 cut in its periphery being designed to engage the nose 105 of the detent. The sleeve of this detent plate is either keyed to or held frictionally on the die hub shaft 106. The die hub 107 is provided with a slot 108 cut through the circumference to the bore, while a bolt 109, 110 passing tangentially through the hub and at right angles to the slot, serves to clamp the hub on the shaft 106, over the detent plate sleeve. This method of mounting the die hub allows it to be moved around and set in any position with respect to the detent plate, and, as the correct cancellation of mail is dependent on the position of the die hub with respect to that portion of the detent plate with which the detent engages, 115 the necessity of this adjustable feature is apparent.

The die hub shaft 106 has a suitable bearing 110 in the upper bed plate *e*. A steady-bearing 111, set in the bracket 112, 125 suffices to relieve all transverse strains due to operation. Directly below the upper bed plate, the die hub shaft 106 penetrates the copper cylinder 113 (which in practice is shrunk upon it) and rests on a thrust bear- 130

ing composed of the ball 114, set in the upper end of the main shaft 115. The copper cylinder 113 is the follower of the driver, which moves the die hub. The leader is composed of the brass cylinder 116, slotted out alternately from the top and bottom thereof, thus making adjacent slots open at opposite ends of the cylinder. Rings 117 and 118 (of some magnetizable substance, preferably mild steel) are boxed out to the external diameter of the cylinder 116 and their faces are slotted, as shown in Figs. 14, 15 and 16. Magnetizable L-shaped fingers 119 are mounted on these rings, the treads 119^a being riveted in the slots 117^a and 118^a, and the projections 119^b extending into the bore of the rings a distance equal to the thickness of the brass cylinder. The pitch of the fingers on each ring is equal to the pitch of alternate slots in the brass cylinder, and, when pressed on the cylinder from opposite ends, constitute an annular cylinder built up of alternate segments of brass and steel, the rings 117 and 118 serving as flanges for holding on the winding and also to provide a magnetic path of low reluctance between every other steel segment. The lower face of the ring 118 is blended into a pseudo-spherical collar which fits over the main shaft 115 and serves to hold the whole cylinder solidly thereon by a suitable set screw 120 and key 121. On this spool shaped cylinder, a suitable coil of wire 122 is wound, one end of which is grounded to the cylinder itself, while the other end is led out to the slip ring 123. This slip ring is mounted on a fiber ring 124 (acting as an insulator) carried by the brass cylinder 125, which is pressed over the whole of this leader, where it is held by frictional contact with the feed rings 118 and 117 and performs its function as a shield for the winding.

In the above described driver, a mechanically-rotating magnetic field is used. The winding 122 is supplied with direct current from the generator *g* (the circuit of which will be brought out later) and the magnetic flux due to this winding is concentrated at the poles 119. Being rigidly supported on the main shaft 115, it rotates with the latter and the magnetic field being thus constantly changed with respect to the follower 113, diminutive electrical currents are induced in the periphery of said follower, and the tendency of these being to follow the leader by the magnetism therein, the follower 113 will rotate in unison with the leader, providing there is no restraining force to the said member 113. But the function of the detent 101 is to provide this restraining force, and at the proper moment; for the die hub, being rigidly connected to the follower, rotates with that member, and is started and stopped intermittently by the engagement

and disengagement of the nose of the detent with notch 105 in the detent plate.

The stud 126 is mounted on the lower bed plate, the lower extremity extending through the plate inside the insulating bushing 127. A suitable nut 127^a is threaded on to this projection and serves to hold the stud insulated from the body of the machine. The upper end of this stud terminates in annular projections, bifurcated in such a manner as to form a clamp for the brush holder 128, this annular bifurcation being tightened around the brush holder 128 by the screw 129. This brush holder 128 consists of a tube which holds the brush 130 and the cap 131 threaded on to the tube presses against the spiral spring 132, which in turn presses upon the brush and keeps it in contact with the slip ring 123.

The main shaft 115, which is the prime moving medium for the whole mechanism, passes through the lower bed plate *b* into the column *a*, and having a suitable bearing 133 in the said bed plate and a bearing 134 carried by the bracket 135, which is secured to the lower bed plate by cap screws 136. Studs 137 fit in holes in the lower bed plate and thus assure the correct alinement of the two bearings. A thrust bearing, composed of a ball 138 set in a cupped screw 139 threaded in to the bearing housing of the bracket 135, serves to support the main shaft vertically, and, at the same time, allows a vertical adjustment which is maintained by the lock nut 140. The main shaft 115 is driven by the motor *m*, through the medium of the motor sheave 141, the drive belt 142, the idler sheaves 143 and the sheave 144. The sheaves 143 are mounted in the bifurcated end of the studs 145, where they are held by the pins 146, on which they are capable of a rotary motion. That end of the bifurcated portion of the studs 145 which holds the pins 146 is out of line with the stud a distance equal to the radius of the sheave 143, and the studs, 145, being capable of a pivotal movement in the bearings 147, where they are secured on the forward ends by the shoulders 148 and the rear ends by the screw threads and nuts 149 and 150, the sheaves 143 can be moved on the studs 145 as a center without disturbing the relation of the grooves on sheaves 143 with respect to the groove or sheave 144. This method allows the diameter of sheave 141 to be varied to suit motors of different speeds.

The ink pump shown in the plan is composed of the solenoidal magnet 151, into which the plunger core 152 slides and the pump cylinder 153, in which the piston 154 slides. The piston rod 155 is threaded into the piston at one end, and into the plunger core at the other end. A spiral spring 156 is under compression, between the shoulder 157 on the core and the end of the magnet, 130

and tends to keep the core out of the magnet. A projection 158 on this shoulder is designed to engage alternately the arms 159 and 160 of the pump contactor 161. This contactor 161 walks on a pin 162, set in the forked block 163, and is held down against either the block 164 or block 165, depending on which side of the pin 162 (which is the center of movement) the spring 166, connected between the upper end of the offset arm 167 and the stud 168, contacts. The block 164 is insulated from the bed plate *e* and carries a platinum tip 169, which contacts with a similar platinum point 170 on the contactor. The block 165 performs no other function than to act as a rest for the contactor, so that the movement of the contactor is the same on either side of the pin 162. The cylinder 163 is covered at one end by a cap 171, which is screwed on, and through which the piston rod 155 passes; while the other end is permanently closed and has leading from it a tube 172, which connects with a suitable ink reservoir 173 (placed preferably on the lower bed plate, as shown in Figs. 1, 2 and 3) and contains a check valve 172^a. Another tube 174 also projects from the cylinder 153, but on the side near the end. This tube also contains a check valve 174^a and is blended into a rectangular mouth, which carries a felt brush 175, this brush pressing against the ink roll idler 176. This ink roll idler 176, which is integral with its shaft, has a bearing in the rear portion of the ink roll frame 177, the said rear portion being formed into an annular tube, which passes through the upper bed plate *e*, and is held in the same by the collar 178, and set screw 179. This frame is capable of a circular motion with the tubular portion as a center, and the shaft of the idler 176, passing through the tube, carries at its lower end the sheave 180, from which it receives motion.

The ink roll 181 is carried on the stud 182, which is a part of the frame, and runs by contact with the idler 176. On that end of the frame remote from the idler, a stud 183 is mounted. This stud has a threaded eye to receive the adjustment screw 184, which, after entering said eye, encounters the pillar 185, against which it is drawn by the spring 186, connected between the stud 187 on the bed plate and the hook 188 on the frame, 177. By this means, the ink roll is adjustable toward the die hub to compensate for wear, and the spring cushions the ink roll frame against the impact of the die-hub or cylinder.

The operation of the inking device is as follows:—Assuming the plunger core 152 to be in such a position that the projection 158 engages the arm 160, the contactor will be carried down toward the block 164 (which is connected to the winding of the magnet 151 by the wire 189) and as soon as the spring 166 passes the pin 162, it will contract, thus drawing the contact points 169 and 170 together and closing the circuit on the magnet 151. The magnet then receives current from the generator *g* (one brush of which is grounded) through the wire 190, the snap switch 191 (which is used to cut out the magnet in case of a too great supply of ink) and the wire 192 (connected between the switch and magnet). This current, after traversing the magnet winding, leaves by the wire 189, the block 164, the contact point 169 and the contact 170, passing onto the frame of the machine and back to the grounded brush of the generator. On the admission of current, the winding becomes energized and sucks in the core 152 which, being positively connected to the piston 154, draws the latter to the front of the cylinder 153. This movement creates a partial vacuum in the cylinder, and the check valve in the tube 172 opens and admits ink from the reservoir 173.

When the plunger 152 has penetrated the magnet, a certain depth, the projection 158 engages the arm 159, pressing the contactor down toward the block 165, and as soon as the spring 156 passes the pin 162, it contracts and, drawing the contactor 161 against the block 165, separates the points 169 and 170, which action opens the circuit on the magnet. The magnet being thus de-energized, the spring 156 then acts to force the plunger out of the core and to drive the piston 154 to the back of the cylinder 153. But the ink in the cylinder retards this motion. It cannot be forced back into the ink reservoir, as the check valve in the tube 172 has closed, but it can enter the tube 174 (by opening the check valve therein) where it saturates the brush 175, from which it is spread on the idler 176 and communicated by the latter to the ink roll 181. When all the ink in the cylinder has been forced out, the projection will be in a position to again close the circuit on the magnet 151, and the same cycle of operations described above will be repeated.

The impression roll 193 is mounted on the shaft 194, where it is held by suitable set screw 195 and carries on its periphery the rubber ring 196. The shaft 194 is journaled at either end in the frame 197, which is provided with ribs 198 adapted to slide in the guideway 199, cut in the upper bed plate. A flat U-shaped spring 199^a is bolted to the bed plate, by cap screws 200 and, pressing against the back of the frame 197, tends to force it, together with the roll 193 which it carries, in the direction of the die hub; but this movement is limited by the stud 201, which, passing through the plate 202 mounted on the back of the bed plate, carries the nuts 203. The function of the stud 201

and nuts 203 (one of which is a lock nut) is to adjust the impression roll in toward the die hub, to accommodate the thinnest letters, while the spring allows a yielding motion to accommodate the various thickness of mail. On the lower end of the shaft 194 is carried the universal coupling 204, which is held by the set screw 205. The arms 204^a of this coupling are adapted to 5 encompass the ball 206 in the grooves 206^a. The mating member of this coupling is mounted on the top of the coupling rod 208, where it is secured by set screw 209 and its U-shaped arms 207^a are adapted to slide in 10 the grooves 206^b of the ball. The lower end of the rod 208 carries a member 210 (similar to member 204) which is held by the set screw 211, and encircles the ball 212; while the upper end of the impression roll 15 gear shaft 214 carries a member 213 (similar to member 207) which straddles the ball 212 and is held to the shaft by the set screw 215. This universal joint of coupling allows the free movement of the impression 20 roll without affecting its perpendicularity and yet it remains positively driven by the shaft 214, which receives motion from the gear 215^a secured to it, this gear meshing with the drive gear 51 mounted on the main 25 shaft 115. The shaft 214 has a suitable bearing 216, set in the lower bed plate and is prevented from rising out of this bearing by the screw 217 and washer 218. The sheave 219 is also mounted on this shaft and 30 is the prime mover for the idler drive belt 220. This belt 220 is the medium for driving all parts which are not necessarily positively driven. Receiving motion from the sheave 219, it passes over various sub-idlers 35 which serve to properly direct it. These sub-idlers are vertically, horizontally or obliquely disposed and are spoken of as vertical, horizontal or oblique idlers, depending on whether they are perpendicular, 40 parallel or oblique to the bed plate on which they are mounted. The horizontal and oblique idlers are carried on blocks and rotate on screw studs, as shown, while the vertical idlers run on screw studs held by 45 brackets.

Beginning at the sheave 219, belt 220 passes over the vertical sub-idler (mounted on the lower bed plate) up to the vertical sub-idler 222 (mounted on the upper bed 55 plate) thence to the horizontal sub-idler 223, around the sheaves 72 and over the horizontal sub-idler 224. Leaving 224, it encircles the pulley 59, crosses the horizontal sub-idler 225 and drives the stacker star 60 wheel sheave 236, from which it is directed by the horizontal sub-idler 227, to the vertical sub-idler 228. From 228, it passes under the tightener idler 229, over the vertical sub-idler 230, down around the generator 65 sheave 231, and up over the vertical

sub-idler 232, from which it is directed around the auxiliary feed belt sheave 27, to the feed roller sheave 32. The drive belt 220 then passes around the horizontal sub-idler 233, to the horizontal sub-idler 234, 70 from which it winds around the switch idler sheaves 68 to the horizontal sub-idler 235, and re-circles the sheave 219, after passing over the ink roll idler sheave 180, the oblique sub-idler 237 (mounted on the bottom of the upper bed plate), the oblique sub-idler 238 (mounted on the top of the lower bed plate) and the horizontal sub-idler 239 (also mounted on the top of the lower bed plate). 75

The belt tightener idler 229 is mounted in a forked frame 240 and revolves on the stud 241. A hook 242 swivels in the bottom of the frame 240, and a spiral spring 243 connects between this hook and a similar one 244 in the top of the bolt 245. This bolt is threaded into the lower bed plate and is used to increase or decrease the tension on the spring, being held in its adjusted position by the jam nut 246. 80

The disposition of the belt 220, around the sheaves 68 and 72, is such as will tend to keep their respective rollers together, and, any tendency to separate either pair of rollers (which the passage of mail would necessitate) will be met by a strain on the belt 220, which strain will be taken care of by the spring 243, the spring furnishing the necessary elasticity for the said separation. 95

The generator *g* is used to supply current to the electrical devices on the machine and it can be either of the permanent magnet or series type, the preference being with the latter. The pole walls 247 support the pole pieces 248, with the aid of the cap screws 249; while the armature 250, with its commutator 251, is mounted on the shaft 252, journaled in the pillar blocks 253. The pillar blocks are fastened to the lower bed plate by cap screws 254, as are the pole walls 247, which are secured by the screws 255. The armature shaft 252 carries the sheave 231, at its rear end, and receives motion from the belt 220. The brush 256 is grounded on the pillar block, where it is mounted, while the brush 257 is insulated therefrom and has connected to it one end of the field winding 258, the other end of which is connected to the brush holder stud 126, by the wires 190 and 259, to the register magnet, by the wires 190 and 260, and to the detent magnet 95, by the wires 190 and 261. 110

The register *r* is composed of the numerical wheels 262, mounted on the shaft 263, on which they are capable of a rotary motion, 125 so as to bring any of the ten figures (1, 2, 3, 4, 5, 6, 7, 8, 9, or 0) opposite the glass covered openings 264. The shelf 265, with the aid of the screws 266, carries the flat springs 267, the round noses of which 268 are de- 130

signed to fall in the notches 269. These springs hold the wheels normally stationary and yet yield sufficiently to allow the wheels to be moved.

5 The tens, hundreds, thousands, tens of thousands and hundreds of thousands wheels carry on their right sides, near the periphery, the pins 270, and the units, tens, hundreds, thousands and tens of thousands 10 wheels have mounted on their left sides the L-shaped arms 271. These arms 271 are held by studs 272 and are directed toward the centers of the wheels by the flat springs 273. Cams 274, mounted on their hubs 275, 15 are held stationary on the shaft 263, by the set screws 276, and the angled ends of the arms 271 are adapted to slide over the irregular edges of these cams.

The object of the set screws 276 is to allow 20 the rises of the cams to be adjusted with respect to the pins 270. The shaft 263 is held stationary in the U-shaped brackets 277, by the set screws 278, while collars 279 prevent the wheels from moving horizontally, the hubs of said wheels and the hubs 25 of the cams filling all the space on the shaft that might permit any lateral movement. In place of the pins, the unit wheel has mounted on its right side the toothed wheel 30 280. The teeth of this wheel are designed for engagement with the pawl 281, which is mounted in the bifurcated end 282 of the lever 283, where it is movable on the pin 284. A flat spring 285 holds the pawl normally 35 in engagement with the wheel teeth, and, at the same time, allows it to give when moving back over the teeth. The lever 283 acts as the armature of the magnet m^3 with a fulcrum (on the end cap 286) composed of the 40 projections 287 capable of carrying the pin 288, on which lever 283 moves. On the forward end of the lever, a knurled screw 289 and lock nut 290 limit the throw of this end and provide a means for adjusting the 45 throw of the pawl end which is normally held down against the projection 291, by the spring 299^a, connected between the hook 292, on the lever and hook 293 on the frame.

The register magnet m^3 is composed of the 50 end caps 286 and 294 (of some magnetizable substance, preferably iron) secured in some suitable manner to the core 295 (also of some magnetizable substance) on which the winding 296 is wound. The core 295 projects through the caps 286 and 294 a sufficient length for the ends (which are threaded) to pass through eyes 297 of the angular brackets 298 and receive the nuts 299. The brackets 298, which form a support for the 55 magnet, are of some non-magnetizable substance, preferably brass, and are secured to the register frame by the cap screws 300. One end of the magnet winding is connected 60 to the generator brush 257, by the wires 190 and 260, while the other end is connected to

the contact blow out magnet 91 by the wire 301.

The register r is designed to count each piece of mail canceled and, being electrically operated, is capable of being placed at a remote distance from the machine. On the drawings, however, it is shown mounted on the machine and performs its function in the following manner. When the approaching letter hits the switch tongue 73, 70 thus throwing the pawl 75 over against the block 88, the generator circuit is closed on the register magnet m^3 . Although the pawl 75 and block 88 remain in contact only an instant, the time is sufficient to operate the 75 magnet whose winding 296 receives current, which leaves the generator by the brush 257, and passes over the wires 190 and 260. After encircling the winding 296, it passes to the contact blow out magnet 91 (which is 80 insulated from the machine) and thence, by the pivotal bearings 89 and 90, to the block 88. From 88, it passes to the pawl 75 (which is then in contact with the block and which also is not insulated from the machine) and reaches the generator armature, by the body of the machine and the grounded brush 256. The magnet m^3 , being thus 85 energized, attracts the lever 283, drawing the forward end down against the end cap 90 294, and, raising the pawl 281 (which engages one of the teeth of the toothed wheel 280) moves the units wheel 262 a distance sufficient for the flat spring 267 to fall in the 95 next groove of the wheel and thereby expose the succeeding digit before the opening 264. When the pawl 75 has separated from the block 88, the circuit on the magnet m^3 will 100 be broken and the spring 299 will act to draw the rear end of the lever 283 down, 105 and with it the pawl 281, which, by virtue of the spring 285, is allowed to drop back over the next tooth of the toothed wheel 280. Each time the circuit of the magnet m^3 is 110 closed, by the pawl 75 coming in contact with the block 88, this action will be repeated, the arm 271 in the meantime sliding over the cams 274. When the nine digits have 115 been exposed, by the units wheel, the arm 271 on this wheel will be at the top of the rise on its adjacent cam, and the angular end of the arm will be in a position to engage one of the pins 270 on the tens wheel. The next impulse the magnet m^3 receives, 120 the pawl 281 operates to move the units wheel so that the cipher will be exposed, and the arm 271, on the units wheel, acts against the pin 270, on the tens wheel, exposing the one. When the tens wheel has moved the 125 distance of nine digits, its arm 271 will be in a position to engage the pin 270 of the hundreds wheel, to which it will impart motion. The hundreds wheel moves the thousands wheel, and the thousands wheel the 130 tens of thousands wheel, and the tens of

thousands wheel the hundreds of thousands wheel until, when the digit 9 is exposed by all the wheels, the register necessarily moves back to its starting point.

- 5 The stacker star wheel 302 is mounted on the shaft 303, which has a suitable bearing 304, set in the upper bed plate *e*. Below the upper bed plate, the shaft 303 carries the sheave 236, which (receiving motion from 10 the idler drive belt 220) drives the wheel 302, the arms of said wheel being designed to press against the letters as they accumulate in the stacker tray, composed of the obliquely disposed rods 305, screwed into the 15 upper bed plate directly above an oblique depression in the same. These rods 305 carry at their farther end a plate 306, which, aside from lending rigidity to the tray, serves to keep the rods equally spaced. 20 The plate is secured to these rods by screws 307, which, passing through holes in the plate, penetrate the threaded ends of the rods:

A rail 308, fastened at one end to the 25 plate 306, by the screw 309, and at the other end to the post 310, by the screw 311, serves as the outer fence of the stacker tray, the post 310 being fastened to the upper bed plate *e* by the screw 312. The inner fence 30 of the tray is formed by the rail 303, whose one extremity is fastened to the plate 306, by the screw 314, while the other rests in the slotted upper-end of the post 315, in which slot it is held by the screw 316, the 35 post 315 being held frictionally in a hole in the upper bed plate.

Braces 317, secured, in some suitable manner, to the plate 306 at points 318 and 319, depend obliquely to the lower bed plate *b*, 40 to which they are likewise securely fastened, at points 320 and 321. The stacker star wheel fence 322 is mounted on the upper bed plate directly back of the star wheel and is provided with a slot of sufficient dimensions to allow the arms of the star wheel, 45 when being rotated, to pass through the plate. The fence 322 is bolted to the bed plate by screws 323, through the projections 324, and is provided with a V-shaped slot 325, for the reception of the stacker extension arm 326. This arm is L-shaped, that portion 327 being hinged, at the point 328, in such a manner that its movement downward is limited to a horizontal plane by the 50 shoulder 327^a and upward to a vertical plane by another shoulder 327^b. The leg of the L is provided with a rack 329, which meshes with the gear 330 mounted on the shaft 331, this shaft having a suitable bearing 55 in the upper bed plate and a thrust bearing in the lower bed plate. A collar 332 retains the shaft 331 in its bearings. Mounted also on the shaft 331 is a spiral gear 333, which meshes with its mating spiral 60 334, secured to the slipper rod 335,

which (passing through suitable bearings in the lugs 336 and 337, depending from the upper bed plate) terminates just outside the plate 306, in the crank 338, secured to it in some suitable manner, preferably by a taper pin. A collar 339, set up against the lug 336, relieves the rod 335 from any longitudinal movement.

With an extension arm constructed as described above, quick adjustment to suit various lengths of letters (distinguished practically as long and short letters) is possible, it being only necessary to turn the crank 338, when the motion is transmitted by the rod 335 and spiral gears 333 and 334 to the shaft 331, from which it is communicated by gear 330 to the rack 329. The arm 326, being rigidly connected to the rack 329, then responds to the movement and the arm 326 moves in or out, depending on the direction in which the crank 338 is turned.

In the stacker tray, between the rods 305^a and 305^b, there runs a grooved pulley 340, solid with the stud 341, which revolves in suitable holes formed in adjacent sides of rods 305^a and 305^b. A grooved pulley 342, similar to pulley 340, rotates in a slotted out portion of the upper bed plate on a stud 343, the stud being set up in the upper bed plate, where it is held by the thrust plates 344. On the rods 305^a and 305^b, the sleeves 345 and 346 are carried, being capable of a sliding motion thereon, by virtue of the balls 347, which are interposed between the inner surface of the sleeves and the surface of the rods.

Brackets 348 and 349 are mounted on the sleeves 345 and 346, and, connecting with the stacker back 350, serve to make it integral with the sleeves. A cord 351, connected with the back 350, passes down over the pulley 342, then up over the pulley 340 and downward to a weight 352, the gravitation of which weight serves to keep the stacker back 350 at the top of the stacker tray, when there are no letters in said tray. When letters enter the tray, however, they are forced against the back 350, by the star wheel 302. This action tends to move the back 350 toward the bottom of the tray, and at the same time, to raise the weight 352. As the mail accumulates in the tray, the back 350 is gradually forced backward, while the weight 352 supplies sufficient pressure to keep the hindmost letters upright. 110 When a tray of letters is removed, all restraining force on the back 350 is likewise removed and the weight 352, acting by gravity, returns the back 350 to the top of the stacker tray.

In place of the plain stacker back described above, and as shown in Fig. 1, there may be used the automatic stacker back (which is continuous in its operations without removing the stacked mail) shown on the 115 120 125 130

elevation in Fig. 3, and more in detail in Figs. 5 and 8. The construction of the tray, when the automatic back is employed, is varied somewhat. The rods 305^x and 305^y are depressed slightly below the plane of the other rods and take the place of rods 305^c and 305^d, while oblique tracks 353 and 354 are secured respectively to rails 308 and 313 and posts 310, 315, by suitable screws 308^a and 310^a, as shown. The screws 310^a, besides holding the lower ends of the tracks 353 and 354, also act to sustain the arched frame 355 (which extends over the mail, the stacker tray, and is connected to each post 310). To the plate 306, the projection 356 is added, being integral therewith, as shown. Other modifications made necessary by the use of the automatic stacker back are the removal of that portion of the bed plate *e* directly below the stacker tray and the inversion of the shipper rod bearing 337, so that it stands on the lower bed plate *b*, as shown at 337^a.

The back proper is composed of the frame 358, the slides 359 and the back 360. On the base of the frame 358, the grooved rollers 361 are held by the screw studs 362. These rollers sustain the weight of the frame and its appurtenances, and, at the same time, allow it a movement along the rods 305^x and 305^y. The cross bar of the frame carries the pawl bracket 363, fastened to it by screws 364, while the pin 365 sustains the pawl 366 in the bifurcated portion of the bracket, a spring 267 serving to hold the pawl normally down.

On the base of the frame, a staple 368 is mounted for connection to the cord 351, the said cord extending back over the pulley 342, then up over the pulley 340, and downward to the weight 352, as in the plain stacker back. The uprights of the frame 358 are provided with slots 358^a, for the reception of the slides 359.

The back 360 is composed of three pieces so joined together as to form an apparently solid exterior, blended at the bottom into the shape of a wedge. By forming the back 360 in the shape of a wedge or beveled portion, is to allow the same to easily penetrate between the mail matter, in order to separate the stacked mail from the mail to be stacked, and the interiors between the three pieces form the compartments 369 and 370. These compartments incasing springs 371 and 372. The spring 371 is connected with the back 360, at the point 373, and, running through the compartment 369, connects also with the small block 374, which is movable on a track formed in the slide 359.

The block 374 is limited in its movement upward by the projection 375, and downward by the projection 376, against which it is normally held by the spring 377, connected between the block itself and the lower

extremity of the slide 359. The slide 359 is composed of the part 378 (carrying a T-shaped track 379, which extends from the projection 375 to projection 376) and the part 380, which carries the pin 381 adapted to slide in the track 353. Parts 378 and 380 are united through the slotted out portion 358^a of the upright of frame 358, by the screws 382. That portion 378 of the slide 359 is provided with a rib 378^a (where it enters the slot 358^a) and flanges 378^b which form a suitable track for the back 360, the middle plate of which is cut away on its vertical edge to a depth that will allow the two outside plates to straddle the block 374. This construction provides a sliding track for the back 360. A slide identical to slide 359 is mounted on the opposite upright of the frame 358, where it is movable in a manner similar to 359, the pin 381^a sliding in the track 354. The spring 372 is connected between the block 374^a and the point 373^a on the back 360, the spring running through the compartment 370. A catch 383 is mounted in a bracket 384 secured at the point 385 to the frame 358 and a pin 386 sustains the catch within the bracket allowing it, at the same time, a free movement with the spring 387, serving to hold the rear end of the catch down. Notches 388 and 389 in the back 360 are designed for engagement with the pawls 366 and 368 respectively.

When there are no letters in the stacker tray, the weight 352 holds the stacker back and its appurtenances near the front of the tray, but, as letters enter and are stacked by the star wheel 302, against the back 360, the whole mechanism is moved toward the back of the tray, the pins 381 and 381^a, sliding in the oblique tracks 353 and 354, thus raising the slides 359, and distending the springs 371 and 372. These springs are distended because the back 360 to which they are secured at one end, is held down (by the engagement of the pawl 366 with the notch 389) while the blocks 374 and 374^a, to which they are also fastened, are carried upward with the slides 359. By the time the stacker back has reached the back of the tray, the slides 359 will have reached the top of the uprights of the frame 358 and the springs 371 and 372 will be fully distended. At this moment, the projection 356 acts to disengage the pawl 366 from the notch 389, and the springs 371 and 372 act to raise the back 360 to the top of the frame 358, when the pawl 366 falls in the notch 388. The back 360 will then be above the letters in the tray and the weight 352 will act to bring the frame 358 to the front of the tray. When this action takes place, the slides 359 will be moved down by the oblique tracks 353 and 354 and the block 374 and 374^a will move up the tracks 379 and 379^a to the projections 375 and 375^a.

at the same time distending the springs 377 and 377^a. At the instant the blocks 374 and 374^a meet the projections 375 and 375^a, the movement of the slides 359 act to 5 distend the springs 371 and 372, and, by the time the frame 358 has reached the front of the tray, the straddle frame 355 acts on the pawl 366, liberating the back 360, and the springs 371 and 372 return it 10 to its position in the bottom of the frame 358, the wedge-shaped edge of the back forcing its way between the accumulated letters in the tray. When the back 360 is down, the pawl 383 reengages the notch 389, and the springs 377 and 377^a draw the blocks 374 and 374^a down against the projections 376 and 376^a. The letters of the rear of the stacker back may be forced into some receptacle, or down a chute, which may be disposed adjacent to the said stacker tray, that is to say, when the stacker back is again moving rearwardly from the impact of the letters. In this manner, it is clear that an automatic stacker back is provided. 20 This chute is designated by the numeral 460 and is shown in dotted lines in Fig. 5 of the drawings.

In practice, the operation of the machine is as follows:—When the motor *m* is started, by a suitable switch or rheostat mounted on the face of the column *a*, its motion is transmitted, by the shaft 115, through the gear 51, to the gear 50, which revolves the separator cone and to the gear 215, which drives the impression roll and the idler drive sheave 219, this sheave 219 serving to put all other moving parts of the machine in motion together with the generator *g*. The leader of the die head driver is rigidly connected with the shaft 115 and rotates with the latter, being fed by the insulated brush 257, and travels over the wires 190 and 259, to the brush holder stud 126. From this, it passes to the slip ring 123, and enters the winding 122, from the grounded end of which it returns to the ground brush 256 of the generator. When the die head leader is thus energized, it exerts a strain on the follower 113, tending to rotate the latter with itself. Rotation, however, is prevented by the engagement of the detent 101 with the notch 105 in the detent plate. When letters are placed on the auxiliary feed belt 12, they are forced against the feed belt 31, by the movement of the latter belt 12, and the aid of the assisting arm 7. The separator cone then acts on the letters and tends to force back all except the one which is in intimate contact with the feed belt 31 and feed rubber 34. This letter, by virtue of the superior contacting surface of the feed roller and belts, is forced onto the carrier belt 56 and transferred to the switch idlers 65 and 66, where it hits the switch tongue 73, and throws the pawl

75 into contact with the block 88, closing the circuits simultaneously on the detent magnet 95, and on the register magnet *m*, the circuit of the detent magnet being from the insulated brush 257 of the generator *g*, 70 over the wires 190 and 261, to the magnet winding and thence over the wire 290^b, to block 88, the pawl 75 and the frame of the machine to the grounded brush 256. The circuit of the register magnet is embodied in the description of the register and in the description of the switch its operation is clearly disclosed. When the switch has closed the circuit on the detent magnet, and the register magnet, the letter 75 is counted and the plunger core 100 of the detent magnet 95 rises, lifting the tail of the detent 101, and throwing the nose out of engagement with the notch 105 in the detent plate. At this point, the follower 113 of the die hub driver is free to move and, following the leader around, carries with it the die hub 107, which imprints, on the passing letter, the postmark. When the advancing letter hits the switch 80 tongue, the closing of the circuits which it controls is only momentary, for the pawl 75 (making contact with the block 88 only on the forward movement of the tongue) in returning to its normal position hits the 85 insulated portion of the block 88. This momentary closing of the detent magnet circuit is enough only to lift the core 100 long enough to disengage the detent 101, after which the core drops, allowing the detent, by virtue of its spring 103, to reengage the notch 105, in the detent plate, thus stopping the die hub 107. After passing the printing and 90 impression rolls, the letter is transferred by the stacker idler rolls 69 and 70, to the 95 stacker tray, where it is taken care of by either the automatic or plain stacker back. Each successive letter is treated in the same manner, being transferred from the feed hopper, where it is separated from others 100 to the stacker tray, and receiving in its 105 passage the registration of the postmark.

In Figs. 44, 43 and 47, a slightly different form of switch is shown, the tongue 73 being forked at one end, and between which forks 115 73^a and 73^b the pin 86 plays, as the tongue 73 is oscillated by an advancing letter. In the construction shown in these figures, the switch tongue is operated similar to that shown clearly in Fig. 31, but, instead of 120 having the switch tongue limited in one direction by a pillar, as shown at 80 in Fig. 31, the said tongue is limited by a downward projection 73^b. This downward projection is made integral with an arm 74^a, 125 one end of which is provided with a downwardly projecting sleeve 74^b, while the opposite end is provided with a pin 74^c, as clearly shown in Fig. 48. Between the pins 86 and 74^c, the spring 85 is connected, 130

and, as the switch tongue is operated away from the said projection 73^b, one fork of the said tongue, which in Fig. 43 is in contact with the pin 86, will operate the pawl 75 and cause the same to contact with the member 88, thus closing the circuit. This pawl 75 is moved by the said fork until the pin 86 is slightly past the line y—y, shown in Fig. 44, at which point the spring 85 10 will contact upon the opposite side of the stud 74. After the advancing letter has passed the switch tongue 73, the spring 74^a is brought into action, the tension of which is greater than the spring 85, and will 15 thereby overcome the said spring 85 sufficient to return the switch tongue 73 in its normal position in contact with the projection 73^b, and will also cause the fork 73^a to return the pawl 75 in contact with the pin 20 79, as shown clearly in Fig. 44. The sleeve 74^b of the said arm 74^a fits over the pin or extension 74^b of the said stud, and, to prevent movement of the said arm and sleeve, a screw 74^c is threaded into the said sleeve 25 and the said pin or extension. The switch tongue and the pawl 75 are supported upon the shoulder 75^a of the stud, and is prevented from rising from off the pin 74^b by means of the said sleeve. The spring 74^d 30 has its lower end or extremity secured to the bed plate e, while its upper extremity is secured to the switch tongue, as shown at 73^k in Figs. 43 and 47.

Certain methods of adjusting different parts of this machine have been shown and described, and there has been certain materials and metals and the like set forth, but it is to be remembered that the applicant is not to be restricted to any such limitations; these limitations have been set forth and illustrated in the drawings, for the simple reason, that at the present time they are considered to be the most practical features, so as to provide commercial value for a 45 machine of this design.

The invention having been fully described, so as to set forth its advantages and operation, what is claimed as new and novel is:—

1. In a mail-marking machine; an electric two-part driver having a continuously closed circuit between the parts; a die-cylinder carried by one of said parts; intermittently released means for retarding the part carrying the cylinder; and means for 55 operating the driver.

2. In a mail-marking machine; a driver comprising a leader and a follower; one having a bearing within the other; said leader having a continuously closed circuit 60 for actuating the follower; a die-cylinder carried by said follower; and means for intermittently retarding the follower.

3. In a mail-marking machine; a driver having a continuously closed electric circuit 65 consisting of a leader and a follower; a die-

cylinder carried by said follower; means for intermittently retarding the follower; and means for operating the retarding means to cause the follower to be attracted by the leader.

4. In a mail-marking machine; a driver comprising a leader and a follower having a continuously closed electric circuit between them; a die-cylinder carried by said follower; means for retarding the follower; 75 means for operating the retarding means to cause the follower to be attracted by the leader; and means for furnishing a current to the leader.

5. In a mail-marking machine; a driver comprising a leader and a follower having a continuously closed electric circuit between them; a die-cylinder carried by said follower; means for retarding the follower; 80 means for operating the retarding means to cause the follower to be attracted by the leader; said retarding means having means for cushioning said follower when retarded; and means for furnishing a current to the leader whereby the follower may be attracted.

6. In a mail-marking machine; a driver comprising a leader and a follower having a continuously closed electric circuit between them; a die-cylinder carried by said follower; means for retarding the follower; 85 means for operating the retarding means to cause the follower to be attracted by the leader; and cushioning means for the follower.

7. In a mail-marking machine; a driver comprising a leader and a follower having a continuously closed electric circuit between them; said follower being mounted within the leader with a surrounding space 105 intervening; a die-cylinder carried by the follower; means for retarding the follower; and means for operating the retarding means to cause the follower to be attracted by the leader.

8. In a mail-marking machine; a driver comprising a leader and a follower having a continuously closed electric circuit between them; a die-cylinder carried by the follower; an impression roller for the cylinder; an adjustable spring-tensioned means for cushioning and retarding the follower; and means for liberating the follower.

9. In a mail-marking machine; a die cylinder; an electrical driver therefor comprising a leader and a follower; said follower being movable with the die cylinder; an impression roll operated by the leader; and means for retarding the follower intermittently.

10. In a mail-marking machine; a die cylinder; an electrical driver therefor comprising a leader and a follower; said follower being movable with the die cylinder; an impression roll operated by the leader; and 120 125 130

- electro-mechanical means for intermittently retarding the follower.
11. In a mail-marking machine; a die cylinder; an electrical driver therefor comprising a leader and a follower; said follower being movable with the die cylinder; an adjustable spring-tensioned impression roll operated by the leader; and means for intermittently retarding the follower.
12. In a mail-marking machine; a die cylinder; an electrical driver therefor comprising a leader and a follower; said follower being movable with the die cylinder; an adjustable spring-tensioned impression roll operated by the leader; and electro-mechanical means for retarding the follower.
13. In a mail-marking machine; an electrically operated sectional shaft; a die cylinder carried thereby; a driver for operating the cylinder comprising a leader and a follower; the leader being movable with one section of the shaft while the follower is movable with the other section thereof; and means for retarding the follower.
14. In a mail-marking machine; an electrically driven sectional shaft having a printing member; one section thereof being continuously driven while the other section is intermittently retarded; a driver comprising leader and a follower; the leader being carried by the continuously driven section of the shaft while the follower is carried by the retarded section thereof.
15. In a mail-marking machine; an electrically driven sectional shaft having a printing member; one section thereof being continuously driven while the other section is intermittently retarded; a driver comprising a leader and a follower; the leader being carried by the continuously driven section of the shaft while the follower is carried by the retarded section thereof; and an impression roll driven from the continuously driven section of the shaft.
16. In a mail-marking machine; an electrically driven sectional shaft having a printing member; one section thereof being continuously driven while the other section is intermittently retarded; a driver comprising a leader and a follower; the leader being carried by the continuously driven section of the shaft while the follower is carried by the retarded section thereof; and an adjustable spring-tensioned impression roll driven from the continuously driven section of the shaft.
17. In a mail-marking machine; an electrically driven sectional shaft having a printing member; one section thereof being continuously driven while the other section is electro-mechanically and intermittently retarded; a driver comprising a leader and a follower; the leader being carried by the continuously driven section of the shaft while the follower is carried by the retarded section thereof; and an impression roll driven from the continuously driven section of the shaft.
18. In a mail-marking machine; an electrically driven sectional shaft having a printing member; one section thereof being continuously driven while the other section is intermittently retarded; a driver comprising a leader and a follower; the leader being carried by the continuously driven section of the shaft and provided with windings so as to induce diminutive currents of electricity whereby the follower is attracted while the follower is carried by the retarded section thereof.
19. In a mail-marking machine; an electrically driven sectional shaft having a printing member; one section thereof being continuously driven while the other section is intermittently retarded; a driver comprising a leader and a follower; the leader being carried by the continuously driven section of the shaft and comprising an inner and outer cylinder having windings therebetween to induce diminutive currents of electricity whereby the follower is attracted, while the follower is carried by the retarded section thereof.
20. In a mail-marking machine, a stacker tray, a horizontally movable carriage therein, guides therefor, and a stacker back mounted to move vertically in said carriage.
21. In a mail-marking machine; a stacker tray; a carriage thereon; guides therefor; said carriage having vertically movable members guided therein; said members having guideways; a stacker back movable in said guideways; and means for raising and lowering said stacker back.
22. In a mail-marking machine, a stacker tray, a weight operated carriage having cam operated members, and a stacker-back having means connected to the members to move the back laterally of and from the path of the mail.
23. In a mail-marking machine; a stacker tray; a weight operated carriage having cam operated members; a stacker back operated by said members and means carried by the carriage for holding the stacker back in a lower or upper position.
24. In a mail-marking machine; a mail stacking mechanism comprising a tray; a carriage guided thereon having cam operated members and a stacker back raised or lowered by the movement of said members; and means for locking the stacker back in its raised or lowered position.
25. In a mail-marking machine; a mail stacking mechanism comprising a tray having guide members; a carriage movable thereon having movable members raised and lowered by said guide members; a stacker back movable between said members and

- spring-actuated when the members are raised or lowered; and means upon the carriage for holding the stacker back in its raised or lowered position.
- 5 26. In a mail-marking machine; a mail stacking mechanism comprising a tray having guide members; a weight returned movable carriage thereon having movable members raised or lowered by said guide members; a stacker back movable between said members and spring-actuated when the members are raised or lowered; and means upon the carriage for holding the stacker back in its raised or lowered position.
- 10 27. In a mail-marking machine; a mail stacking mechanism comprising a tray having guide members; a weight returned movable carriage thereon having movable members raised or lowered by said guide members; said carriage being moved rearward by the weight of the mail; a stacker back movable between said members and spring-actuated when the members are raised or lowered; and means upon the carriage for holding the stacker back in its raised or lowered position.
- 15 28. In a stacking mechanism, a stacker back movable by the weight of the mail, means for holding the back in an upper or lower position, and automatic means for releasing it from said positions.
- 20 29. In a stacking mechanism, a stacker back movable by the weight of the mail and holdable in lower and upper positions, means for automatically releasing it, and means put under tension by the movement of the stacker back for moving the stacker back from the path of the mail when it is released.
- 25 30. In a stacking mechanism, a movable stacker back movable from initial position by weight of the mail and having members to hold the back in upper or lower positions, means for automatically releasing said members, and means for returning the back to its initial position.
- 30 31. In a stacking mechanism, a stacker back having a holding member movable by the weight of the mail, means put under tension by the movement of the back, and means for releasing said member, whereby said back is actuated laterally by said tension means.
- 35 32. In a stacking mechanism, a stacker back movable in one direction by the weight of the mail, means put under tension by the movement of the back, means for releasing said tension means, and means for restoring the tension means to their initial position by the return of the back.
- 40 33. A stacking mechanism provided with a vertically movable member, means for holding it in its lowermost position, means put under tension by the movement of the member, and automatic means for releasing the holding means to allow the tensioned means to move said member upward.
- 45 34. A stacking mechanism provided with a vertically movable member, means for holding it in its lowermost position, means put under tension by the movement of the member, automatic means for releasing the holding means to allow the tensioned means to move said member upward, and means for automatically engaging and holding said member in its uppermost position.
- 50 35. In a mail-marking machine; a die cylinder; means operated by an advancing letter for operating the cylinder, said means comprising means for restoring the operating parts of the first-named means to their normal positions; means operated by the restoration of said parts for retarding the cylinder.
- 55 36. In a mail-marking machine; a die cylinder; means operated by an advancing letter for operating the cylinder, said means comprising means for restoring the operating parts of the first-named means to their normal positions; cushioning means operated by the restoration of said parts for retarding and cushioning the cylinder.
- 60 37. In a mail-marking machine; an electrically operated die cylinder; movable means for holding the cylinder; means having an independent electric circuit operated by the advancing mail for releasing the holding means; said last-named means comprises devices for restoring its parts to their normal positions, said parts when restored return the holding means to its normal position.
- 65 38. In a mail-marking machine; an electrically operated die cylinder; movable means for holding the cylinder; means having an independent electric circuit operated by the advancing mail for releasing the holding means; said last-named means comprises devices for restoring its parts to their normal positions, said parts when restored open the circuit and restores the holding means to its normal position; and means for advancing the mail to the cylinder.
- 70 39. In a mail-marking machine; an electrically operated die cylinder; movable cushioning means for holding the cylinder; means having an independent electric circuit operated by the advancing mail for releasing the holding means; said last-named means comprises devices for restoring its parts to their normal positions, said parts when restored open the circuit and restore the holding means to its normal position.
- 75 40. In a mail-marking machine; a die cylinder having a notched member movable therewith; movable means having a cushioning member for engaging the notched member; means having an independent electric circuit operated by the advancing mail for withdrawing the cushioning member.

from the notched member; said last-named means comprises devices for restoring its parts to their normal positions, said parts when restored open the circuit and restore the cushioning member in engagement with the notched member.

41. In a mail-marking machine; a die cylinder having a notched member movable therewith; pivoted means having a cushioning member for engaging the notched member; means having an independent electric circuit operated by the advancing mail for withdrawing the cushioning member from the notched member; said last-named means comprises devices for restoring its parts to their normal positions, said parts when restored open the circuit and restore the cushioning member in engagement with the notched member.

42. In a mail-marking machine; a die cylinder having a notched member movable therewith; oscillatory means having a cushioning member for engaging the notched member, said pivoted means having means for compensating the cushioning action of the said member; means having an independent electric circuit operated by the advancing mail for withdrawing the cushioning member from the notched member; said last-named means comprises devices for restoring its parts to their normal positions, said parts when restored open the circuit and restore the cushioning member in engagement with the notched member.

43. In a mail-marking machine; a die cylinder having a notched member movable therewith, an intermittently operated driver for operating the cylinder; movable means having a cushioning member for engaging the notched member; means having an independent electric circuit operated by the advancing mail for withdrawing the cushioning member from the notched member; said last-named means comprises devices for restoring its parts to their normal positions, said parts when restored open the circuit and restore the cushioning member in engagement with the notched member.

44. In a mail-marking machine; a die cylinder having a notched member movable therewith; an intermittently operated driver for operating the cylinder; pivoted means having a cushioning member for engaging the notched member; means having an independent electric circuit operated by the advancing mail for withdrawing the cushioning member from the notched member; said last-named means comprises devices for restoring its parts to their normal positions, said parts when restored open the circuit and restore the cushioning member in engagement with the notched member.

45. In a mail-marking machine; a die cylinder having a notched member movable therewith, an intermittently operated driver

for operating the cylinder; oscillatory means having a cushioning member for engaging the notched member, said oscillatory means having means for regulating the cushioning action of the said member; means having an independent electric circuit operated by the advancing mail for withdrawing the cushioning member from the notched member; said last-named means comprises devices for restoring its parts to their normal positions, said parts when restored open the circuit and restore the cushioning member in engagement with the notched member.

46. In a mail-marking machine; a die cylinder having a notched member movable therewith; a drive comprising a continuously rotating leader and a follower; said cylinder and the notched member being movable with the follower; movable means having a cushioning member for engaging the notched member; means having an independent electric circuit operated by the advancing mail for withdrawing the cushioning member from the notched member; said last-named means comprises devices for restoring its parts to their normal positions; said parts when restored open the circuit and restore the cushioning member in engagement with the notched member.

47. In a mail-marking machine; a die cylinder having a notched member movable therewith; a driver comprising a continuously rotating leader and a follower; said cylinder and the notched member being movable with the follower; pivoted means having a cushioning member for engaging the notched member; means having an independent electric circuit operated by the advancing mail for withdrawing the cushioning member from the notched member; said last-named means comprises devices for restoring its parts to their normal positions, said parts when restored open the circuit and restore the cushioning member in engagement with the notched member.

48. In a mail-marking machine; a die cylinder having a notched member movable therewith; a driver comprising a continuously rotating leader and a follower; said cylinder and the notched member being movable with the follower; oscillatory means having a cushioning member for engaging the notched member; said oscillatory means having means for regulating the cushioning action of said member; means having an independent electric circuit operated by the advancing mail for withdrawing the cushioning member from the notched member; said last-named means comprises devices for restoring its parts to their normal positions, said parts when restored open the circuit and restore the cushioning member in engagement with the notched member.

49. In a mail-marking machine; an elec-

- trically operated die cylinder having a notched member movable therewith; a direct connected driver for the cylinder; means for operating the driver; pivoted means having 5 a cushioning member for engaging the notched member; means having an independent electric circuit operated by the advancing mail for withdrawing the cushioning member from the notched member; said 10 last-named means comprises devices for restoring its parts to their normal positions; said parts when restored open the circuit and restore the cushioning member in engagement with the notched member.
- 15 50. In a mail-marking machine; an electrically operated die cylinder having a notched member; a direct connected driver for the cylinder; means for operating the driver; pivoted means having a cushioning member for engaging the notched member; non-corrosive means having an independent electric circuit operated by the advancing mail for withdrawing the cushioning member from engagement with the notched member; said non-corrosive means comprises devices for restoring its parts to their normal positions; said parts when restored open the circuit and restore the cushioning member in engagement with the notched member.
- 20 51. In a mail-marking machine; an operative die cylinder; means for preventing the cylinder from operation; non-corrosive means for operating the first-named means, thereby allowing the cylinder to operate; 25 said first-named means adapted to retard the cylinder after being once operated and provided with means for cushioning the cylinder.
- 25 52. An automatic mail-marking machine; 30 means including a stacker back for automatically and continuously backing up the mail; means for removing the back from the path of the mail without removing the stacked mail; and means for replacing the 35 back in advance of the mail.
- 30 53. In a mail-marking machine; means for automatically canceling the mail as it advances; means including a member for automatically and continuously backing up the 35 mail; means for removing the member from the path of the stacked mail and returning it in advance thereof without removing the stacked mail.
- 35 54. An automatic mail-marking machine; 40 means including a member for automatically and continuously backing up the mail without removing the stacked mail; means for removing the member from the path of the stacked mail and returning it in advance thereof without disturbing said stacked mail; said member being designed to discharge the stacked mail.
- 40 55. An automatic mail-marking machine; 45 means for automatically and continuously backing up the mail without removing the stacked mail; and means for preventing corrosion thereof.
- 45 56. An automatic mail-marking machine; 50 means including a member for backing up the mail; means for releasing the member after backing the mail; means for removing the member from the path of the stacked mail and moving it past the stacked mail; means for again releasing the member; and means for placing the member in advance of the stacked mail.
- 50 57. In a mail-marking machine; a stacking mechanism including the stacker-back adapted to move under the accumulation of mail matter; means in the path of the stacker-back for tripping the same and permitting it to return to its initial position; and means for raising the stacker-back and so returning it over the stacked mail to its initial position.
- 55 58. In a stacking mechanism, a stacker back movable by the accumulation of mail; means for returning the back in advance of the stacked mail to its initial position without removing said stacked mail.
- 60 59. A mail-marking machine having a stacker back movable by the mail; means for removing the back from the path of the mail and placing it in advance of the stacked mail in its initial position.
- 65 60. In a mail-marking machine; an operable printing member; said machine having a stacker back movable by the mail; means for removing the stacker back from the path of the mail; and means for placing it in advance of the stacked mail in its initial position.
- 65 61. In a mail-marking machine; a normally retarded printing member having a follower; a leader loosely surrounding the follower; means for energizing the leader in order to drive the follower when released, without engaging the follower.
- 70 62. In a mail-marking machine; a normally retarded printing member having a follower; a leader surrounding the follower with a space intermediate the leader and the follower; means for energizing the leader to drive the follower when released; and means for operating the retarding means of the printing member.
- 75 63. In a mail marking machine; a normally retarded printing member having a follower; a leader loosely surrounding the follower and having means to drive the follower when released; and means for releasing the retarding means of the printing member; said means including an electric circuit and a device in the circuit for opening and closing the same, said device having means for preventing corrosion thereof.
- 80 64. In a mail marking machine; an inter-

- mittently operated printing member; controlling means therefor including an electric circuit and a device in the circuit for opening and closing the same; said device having means for preventing corrosion thereof.
65. In a mail marking machine; a retarded printing member; controlling means therefor including an electric circuit and a device in the circuit for opening and closing the same; said device having means for preventing corrosion thereof and means for cushioning the member when retarded.
66. In a mail marking machine; a stacking mechanism including a stacker back adapted to move under the accumulation of mail matter; means for tripping the stacker back; means for removing the back from the path of the stacked mail without removing the stacked mail and permitting it to return to its initial position; and means for so returning said stacker back to its initial position.
67. In a mail marking machine; an electric driver having a continuously closed circuit and consisting of a leader and a follower; a die cylinder carried by the follower; and means for intermittently retarding the follower.
68. In a mail marking machine; a driver consisting of a permanently non-frictional engaging leader and a follower; said follower being adapted to follow the leader; a die cylinder carried by the follower; and means for intermittently retarding the follower.
69. In a mail marking machine; a driver consisting of a non-frictional engaging leader and a follower; said leader having means to cause the follower to rotate there-without frictional contact; a die cylinder carried by the follower; and means for intermittently retarding the follower.
70. In a mail marking machine; a driver consisting of two non-frictional engaging members and including an electric circuit continuously closed; said circuit adapted to cause one member to follow the other member without friction; a die cylinder carried by the following member; and means for intermittently retarding the following member.
71. In a mail marking machine; the combination of a printing member and an impression roll; of a carrier belt traveling between and below the member and the roll; idler rolls located forwardly and rearwardly of the printing member and the impression roll; a controlling switch mechanism for the printing member located in proximity to two of the idler rolls and having a letter-operated member adjacent the said last-mentioned idler rolls and including an electric circuit; and a device in the circuit for opening and closing the same.
72. In a mail marking machine; the combination of a printing member and an impression roll; idler rolls located forwardly and rearwardly of the printing member and the impression roll; a controlling switch mechanism for the printing member located in proximity to two of the idler rolls and having a letter-operated member adjacent the said last-mentioned idler rolls and including an electric circuit; and a device in the circuit for opening and closing the same.
73. In a mail marking machine; a printing member having idler rolls located forwardly and rearwardly thereof; controlling means for the member including an electric circuit and a device in the circuit for opening and closing the same; said device having a finger adjacent the forward rolls, whereby the action of said device is governed; said device being provided with means for preventing corrosion of the finger.
74. In a mail marking machine; a printing member; controlling means therefor including an electric circuit and a device in the circuit for opening and closing the same; said device having means whereby its action is governed and provided with means for preventing corrosion thereof.
75. In a mail marking machine; a stacker tray having guideways; a stacker extension arm mounted in said guideways; said stacker extension arm having a rack; a pinion engageable with said rack; and means for operating the pinion whereby the stacker extension arm may be horizontally adjusted.
76. In a mail marking machine; a stacker tray having guideways; a stacker extension arm mounted in said guideways; said stacker extension arm having a rack; a pinion engageable with said rack; and a pair of shafts geared together for operating the pinion whereby the stacker extension arm may be adjusted.
77. In a mail marking machine; a driver consisting of a leader and a follower; said follower having a thrust bearing within the leader and provided with a printing member; and a bearing for the upper end of said follower.
78. In a mail marking machine; a driver consisting of a leader and a follower spaced apart; said follower having a thrust bearing within the leader and provided with a printing member; and a bearing for the upper end of said follower; said leader adapted to cause the follower to move therewith.
79. In a mail marking machine; the combination of a pair of pivoted idler rolls having pulleys; of a carrier belt; and means cooperating with the pulleys for holding the idler rolls yieldably in close proximity to one another.
80. In a mail marking machine; the com-

- bination of a pair of pivoted idler rolls; of a carrier belt; said idler rolls having shafts provided with pulleys on their lower ends; and a belt so connected with said pulleys 5 as to hold the idler rolls yieldably in close proximity to one another.
81. In a mail-marking machine; the combination of a die cylinder and an impression roll; of a frame for said roll; guides 10 for said frame; and an arched bowed spring having an adjustable connection with said frame whereby the impression of the roll may be governed.
82. In a mail-marking machine; the combination of a die cylinder and an impression roll; of a frame for said roll; guides 15 for said frame; an arched bowed spring having an adjustable connection with said frame whereby the impression of the roll may be governed, and connections between 20 the impression roll and the cylinder whereby they may be operated in unison.
83. In a mail-marking machine; the combination of a die cylinder and an impression roll; of a frame for said roll; guides 25 for said frame; an arched bowed spring having an adjustable connection with said frame whereby the impression of the roll may be governed; said cylinder having a 30 driven shaft; said impression roll having a flexible sectional coupled shaft; and means of connection between the shafts whereby the cylinder and the impression roll may be rotated in unison.
84. In a mail-marking machine; an electrical driver comprising a continuously revolving leader and an intermittently retarded follower; means for retarding the follower, a die-cylinder carried by said follower; means for furnishing a magneto-current to the leader whereby the follower, when not retarded, may be attracted by the leader and driven thereby.
85. In a mail-marking machine; an electric driver comprising a non-contacting leader and a normally retarded follower spaced apart; means for retarding the follower, a die-cylinder carried by said follower; and means for furnishing the magneto-current to the leader, whereby the follower, when not retarded, may be attracted by the leader and driven thereby.
86. In a mail-marking machine; an electric driver comprising a permanently spaced apart leader and a normally retarded follower; means for retarding the follower, a die-cylinder carried by said follower; means for furnishing the magneto-current to the follower, whereby the follower, when not retarded, may be attracted by the leader and driven thereby; and means for releasing the follower.
87. In a mail-marking machine; a driver comprising a continuously revolving member and a normally retarded non-engaging
- member permanently arranged without frictional engagement; said continuously revolving member being energized to drive the normally retarded non-engaging member; means to release the normally retarded member, and a die-cylinder carried by the retarded member.
88. In a mail-marking machine; a driver consisting of a leader and a follower; said follower having an independent bearing 75 within the leader and provided with a printing member; and a bearing for the upper end of the follower.
89. In a mail-marking machine; a driver 80 consisting of a leader and a follower; said follower having an independent bearing within the leader and provided with a printing member; a bearing for the upper end of the follower; and an impression member for the printing member.
90. In a mail-marking machine; a driver 85 consisting of a leader and a follower; said follower having an independent bearing within the leader and provided with a printing member; a bearing for the upper end of the follower; and an impression member geared to the leader.
91. In a mail-marking machine; a printing member having idler rolls located forwardly and rearwardly thereof; controlling 95 means for the member including an electric circuit and a device in the circuit for opening and closing the same; said device having a finger adjacent the forward rolls whereby its action may be governed; said device being provided with means for preventing corrosion of the finger; said controlling means having cushioning means for the printing member.
92. In a mail-marking machine; a driver 100 comprising a leader and a follower having a continuously closed circuit between them; said follower being mounted within the leader with a surrounding space intervening; said follower having a bearing within 105 the leader; a bearing for the upper portion of the follower; a die cylinder carried by the follower; and means for retarding the follower.
93. In a mail marking machine; a stacker 110 back; said back being holdable into and out of coöperation with regard to the mail and having means to move the back laterally from and into the path of the mail; said back being releasable from said holding means.
94. In a mail marking machine; a driver 115 comprising a leader and a follower; said follower being mounted within the leader with a surrounding space permanently intervening; said follower having a bearing within the leader; a bearing for the upper portion of the follower; a die cylinder carried by the follower; and means for retarding the follower.

95. In a mail marking machine; a stacker tray; a weight-operated carriage having cam-operated members; and a vertically movable stacker back having means connected to the members to move the back vertically.
96. In a mail-marking machine; a driver comprising a rotating part and an intermittently retarded part having a printing member; means for retarding the retarded part; said parts being at no time in material contact with each other; and means for driving one part through the medium of the other.
97. In a mail-marking machine, a stacker tray, a horizontally weight operated carriage having cam operated members, and a stacker-back having means connected to the members to move the back laterally of and from the path of the mail, and means for holding the back in and out of the path of the mail.
98. In a stacking mechanism, a stacker back, spring actuated vertically and movable horizontally by the weight of the mail, means for holding the back in upper and lower positions against the tension of said spring, and automatic means for releasing it from said positions.
99. In a stacking mechanism, a vertically actuated stacker-back, said back being horizontally movable by the weight of the mail, said back being holdable in lower and upper positions in and out of coöperation with the mail, means for automatically releasing it from said positions, and means put under tension by the vertical movement of the back for moving the back into and out of coöperation with the mail when it is released.
100. In a stacking mechanism, a horizontally and vertically actuated movable stacker-back, members to hold the back in one or more positions when the back reaches its limit in either direction during its vertical movement, means for automatically releasing said members, and means for returning the back to its initial position after being moved horizontally.
101. In a stacking mechanism, a horizontally and laterally actuated movable stacker-back, means for holding the back in
- and out of coöperation with the mail, means put under tension by the lateral movement of the back, means for releasing said holding means, whereby said back is actuated laterally of the horizontal movement by said tension means.
102. In a mail-marking machine; the combination of printing and impression means, of idler rolls located forwardly and rearwardly of the printing and impression means; combined with inking means and separating means, of mail-advancing means traveling below and between the idler rolls and the printing and impression means; said printing means, impression means and a portion of the separating means being positively geared together; endless means for operating a portion of the separating means and the idler rolls in unison, said endless means connected with the printing and impression means to cause the idler rolls and the mail-advancing means to move in unison therewith; and means for tensioning the endless means.
103. In a mail marking machine, a driver comprising a constantly rotating part and an intermittently retarded part having a printing member; means for retarding the retarded part; said parts being at no time in material contact with each other; means for driving one part through the medium of the other; and means for cushioning the retarded part when retarded.
104. In a mail marking machine; a driver comprising a constantly rotating part and an intermittently retarded part having a printing member; said parts being at no time in material contact with each other; controlling means for the retarded part, including an electric circuit and a device in the circuit for opening and closing the same; said device having means for preventing corrosion thereof; and means for driving one part through the medium of the other.

In witness whereof, my signature, is hereunto affixed in the presence of two witnesses.

FRANCIS G. BOSWELL.

Witnesses:

A. L. HOUGH,
ROBERT A. BOSWELL.
